UNITED STATES PATENT OFFICE

2,401,375

INTERNAL-COMBUSTION ENGINE

James G. Shepard, Toronto, Ontario, Canada

Application June 9, 1944, Serial No. 539,518

5 Claims. (Cl. 123—50)

1

The present invention relates to improvements in internal combustion engines of the two-stroke cycle type and the principal object of the invention is to effectively increase the efficiency of the engine while reducing the stresses upon the cylinder and pistons by applying the force of the explosions in opposite directions to develop a balanced torque in the crank shaft.

A further object of the invention is to ensure a uniform vaporization of fuel and carburetion of air entering the cylinder at all speeds.

The principal feature of the invention consists in the novel construction and arrangement of parts whereby a piston operatively connected to a crank of the crank shaft operates within a reciprocating cylinder piston operatively connected with cranks of the crank shaft arranged in opposed relation to the aforesaid crank, said cylinder piston operating within a fixed cylinder having an air intake port and a discharge port leading through a carburetter to an inlet port which connects with the combustion chamber.

In the accompanying drawings

Figure 1 is a longitudinal mid-sectional view through an engine and carburetter constructed in accordance with this invention, the pistons being shown in the firing position at the point of highest compression.

Figure 2 is a longitudinal mid-sectional view through the engine showing the pistons at the limit of the outward or power stroke.

Figure 3 is a cross section through a portion of the carburetter on the line 3—3 of Figure 1.

Figure 4 is an elevational detail of the carburetter and air tube leading thereto taken at right angles to the illustration of Figure 1.

Referring to the accompanying drawings, the engine base 1 has journalled therein a crank shaft 2 which is formed with a central crank 3 and cranks 4 arranged at either side of and in opposed relation, 180 degrees, to the crank 3.

Mounted on the base 1 is the stationary cylinder 5, the lower portion 6 of which is of lesser diameter than the upper portion 7.

Mounted within the cylinder 5 is a reciprocating cylinder 8 which slidably engages the inner wall of the lower portion 6 thereof and is provided with an enlarged piston head 9 operating within the upper portion 7 of said cylinder 5, said piston head being provided with suitable spaced-apart piston rings 10.

A radial inlet port 11 extends through the wall of the piston head 9 between the rings 10 and forms a communicating port between the upper

2

end of the interior of the cylinder 8 and an inlet port 12 in the wall of the stationary cylinder 5.

Connecting rods 13 are mounted on wrist pins 14 secured to the lower end of the reciprocating cylinder 8 and connect the said cylinder 8 with the paired cranks 4.

A piston 15 is arranged to reciprocate within the cylinder 8 and is connected with the crank 3 by a connecting rod 16.

The dimensions of the cylinder 8, piston 15 and their connecting rods are such that when the centre crank 3 is in its uppermost position and the cylinder 8 is in the lowermost position, as shown in Figure 1, the combustion chamber 17 will be of the required dimensions to produce the desired compression of combustion gases, the inlet port 11 to said cylinder being closed by the cylinder wall 8 and sealed by the piston rings 10.

An air inlet port 18 is arranged in the wall of the cylinder 5 in such a position that it will be uncovered by the piston head 9 when the cylinder 8 is in its lowermost position, allowing air to flow into the interior of the cylinder 5.

The cylinder 5 is closed by a head 19 which is formed with an air compression chamber 20.

Secured to the side wall of the cylinder 5 at the outer end of the inlet port 12 is a carburetter 21 in which is mounted a rotatable throttle valve 22 operated by a spindle 23, said valve having openings 24 therein to register with corresponding openings in a throttle plate 25 mounted in the carburetter passage 26.

A tube 27 opening into the side wall of the carburetter 21 is provided with a suitable venturi 28 and a fuel jet 29 to which fuel is fed from the float chamber 30, the flow of fuel being regulated by a needle valve 31.

A tube 32 opening from the air compression chamber 20 communicates with the tube 27 below the venturi and directs air compressed in said chamber around the fuel jet into the venturi. The air, being under compression effected by the upward movement of the piston head 9 of the cylinder 8, flows with uniform velocity through the carburetter upon the opening of the inlet port 11 into the cylinder 8.

An exhaust port 33 is arranged in the side wall of the cylinder 5 and a port 34 is arranged in the cylinder 8 to register therewith, both ports being uncovered by the piston 15 as it approaches the lower end of its stroke to permit the escape of the products of combustion, such escape being assisted by the inflow of a charge of carburetted air through the inlet port 11 in the cylinder 8 which opens the inlet 12 from the carburetter

3

coincident with the opening of the exhaust port 33.

A suitable port 35 is arranged between the exhaust port 33 and the cylindrical space between the piston head 9 and the reduced portion 6 of cylinder 5 to release compression occurring as the piston head 9 moves downwardly.

A spark plug 36 for igniting the combustible charge in the cylinder 8 is mounted centrally of the cylinder head 9 and a contact rod 37 extends therefrom through a suitably insulated packing gland 38 and engages spring contacts 39 connected with the high tension terminal 40 arranged in a cap 41.

It will be understood that upon the ignition of the compressed charge within the cylinder 8 the expansion of the charge forces the piston 15 downwardly and the reciprocating cylinder 8 upwardly, thus simultaneously applying a pushing stroke to the crank 3 and a pulling stroke to the cranks 4. The cylinder head moves upwardly while the piston moves downwardly the full crank stroke, consequently the effective longitudinal dimension of the combustion chamber is twice the crank stroke.

Since the stroke of the piston cylinder 8 is only one half the stroke of the piston 15 relative to said piston 8 the area of the piston head 9 will be twice the area of the piston 15 in order that the displacement of both pistons will be equal. At the moment of ignition the compression chamber 20 is filled with air at atmospheric pressure through the inlet port 18, and the upward movement of cylinder head 9 closes the port and compresses the air in the chamber 20.

At a predetermined point, approximately 30 degrees in advance of dead centre, the exhaust port 34 and inlet port 11 in cylinder 8 commence to open. The products of combustion escape from the bottom of the cylinder 8 above the piston 15 and the compressed air from the chamber 20 flows through the tubes 32 and 27 to and through the venturi 28 of the carburetter into the top end of the cylinder through the ports 12 and 11, thus thoroughly scavenging the burnt gases from the cylinder. The flow of air from the compression chamber through the venturi 28 creates a uniform and highly vaporized mixture and such flow will be uniform at all speeds of engine operation and ensures the utilization of the full volumetric capacity of the cylinder independent of the speed of the piston travel, which is in effect similar to a supercharger.

The movement of the pistons closes the exhaust and intake ports at approximately 30 degrees past dead centre and the cylinder 8 and piston 15 then move toward each other in the compression cycle until firing again takes place and the cycle is repeated.

The double crank action produced by the double piston movement relieves the bearings of the crank shaft of considerable stress over an engine where the thrust is in one direction. Further, the extra length of combustion space ensures the maximum power value, and when such elongated expansion stroke is obtained the firing compression may be greatly lessened and so reduce the cylinder head stresses.

What I claim as my invention is:

1. In an internal combustion engine, a fixed cylinder, a crank shaft having oppositely disposed cranks, a cylinder piston operable in the aforesaid cylinder and operatively connected to one of said cranks, a piston operable within said cylinder piston and operatively connected to the

4

other of said cranks, a compression chamber arranged at the head of said fixed cylinder and having an inlet port controlled by said cylinder piston, a carburetter having an inlet port connected with said compression chamber and a discharge port opening to the fixed cylinder adjacent to the top, an inlet port in said cylinder piston adjacent to the top thereof and directing carburetted air to the interior of the cylinder piston at the upper end of its stroke, and an exhaust port controlled by said piston cylinder.

2. In an internal combustion engine, a stationary cylinder, a reciprocating cylinder mounted in said stationary cylinder, a piston operating in said reciprocating cylinder, a crank shaft having a centrally arranged crank and a crank arranged at each side of said central crank and opposed thereto, a connecting rod connecting the central crank with said piston, a pair of connecting rods connecting said reciprocating cylinder with the pair of opposed cranks, a compression chamber arranged at the top of said stationary cylinder having an inlet through the side wall of the cylinder controlled by the reciprocating cylinder and arranged immediately above the top of said reciprocating cylinder when said cylinder is at the lower limit of its stroke, said stationary cylinder having a second inlet port arranged intermediate of the stroke of the head of the reciprocating cylinder, said reciprocating cylinder having an inlet port adapted to communicate with the latter inlet port in the stationary cylinder when said reciprocating cylinder approaches the upper limit of its stroke, a carburetter having its discharge connected with the upper inlet port in the stationary cylinder, a duct connecting said compression chamber with said carburetter and compressed air therethrough during the upward stroke of the reciprocating cylinder, and a port through the wall of the upper end of said cylinder piston adapted to connect with the port from the carburetter at the upper end of the stroke of the reciprocating cylinder.

3. In an internal combustion engine, a stationary cylinder having the upper portion of its bore of a diameter larger than the lower portion, a reciprocable piston cylinder slidably engaging the lower and smaller bore of the stationary cylinder and having an enlarged head slidably engaging the larger upper bore of the cylinder, spaced-apart piston rings mounted in the enlarged head of said reciprocating piston cylinder, an inlet port extending through the wall of the enlarged head of the reciprocating cylinder between said piston rings, an inlet port arranged in the wall of the stationary cylinder adapted to register with the inlet port in the reciprocating cylinder as said reciprocating cylinder approaches the outward ends of its stroke, an intake port arranged in the wall of the stationary cylinder and adapted to be uncovered by said reciprocating piston cylinder as it approaches the end of its downward stroke, a compression chamber arranged at the upper end of the stationary cylinder, a carburetter arranged to discharge into the upper inlet port in the stationary cylinder, a duct leading from the compression chamber to said carburetter to direct compressed air thereto, an exhaust port in the side wall of the stationary cylinder, an exhaust port arranged intermediate of the length of the reciprocating piston cylinder adapted to register with the exhaust port in the stationary cylinder and adapted to be un-

covered by the piston operating in said reciprocating piston cylinder as said piston approaches the downward limit of its stroke, a crank shaft having a central crank operatively connected with said piston, and cranks arranged either side of said central crank and opposed thereto and operatively connected with said reciprocating piston cylinder.

4. In an internal combustion engine, a stationary cylinder having an enlarged bore at its upward end, a reciprocating piston cylinder arranged in said stationary cylinder having an enlarged head operating in the upper enlarged bore thereof, a piston operating in said reciprocating cylinder, a crank shaft having a central crank and opposed cranks arranged at either side thereof, a connecting rod connecting said central crank with said piston, wrist pins mounted on the lower end of said reciprocating piston cylinder, connecting rods connecting said wrist pins with the cranks either side of the central crank, a compression chamber at the top of said sta-

tionary cylinder having an intake port at the lower end thereof and an inlet port intermediate of the length thereof, an inlet port in the enlarged head of the reciprocating piston cylinder adapted to connect the intermediate inlet port with the combustion chamber between the head of the piston cylinder and the piston operating therein, a carburetter connected with the inlet port, a port leading from the compression chamber to the carburetter, and means carried by said reciprocating piston cylinder for igniting the explosive charge in the combustion chamber.

5. An internal combustion chamber as claimed in claim 1, having a spark plug mounted in the head of the reciprocating piston cylinder and having an extension contact rod extending through the compression chamber, contact means arranged above said compression chamber engaging said spark plug extension in sliding contact, and sealing means surrounding said slidable extension.
